UNITED STATES PATENT OFFICE.

JAMES M. GARDINER, OF HACKENSACK, NEW JERSEY, ASSIGNOR TO THE GAMEWELL FIRE ALARM TELEGRAPH COMPANY, OF NEW YORK, N. Y.

ELECTRO-MAGNETIC ESCAPEMENT MECHANISM.

SPECIFICATION forming part of Letters Patent No. 256,994, dated April 25, 1882.

Application filed June 27, 1881. (No model.)

To all whom it may concern:

Be it known that I, JAMES M. GARDINER, of Hackensack, in the county of Bergen, State of New Jersey, have invented a new and useful Electro-Magnetic Escapement Mechanism, of which the following is a specification, reference being had to the accompanying drawings, forming part of the same, in which—

Figure 1 is a side elevation of an apparatus 10 containing my invention, and Fig. 2 is an edge view of the same.

My invention relates to an electro-magnetic escapement mechanism; and it consists in the combination, with an electro-magnet, of the 15 duplex locking and releasing mechanism hereinafter described and claimed.

A is a spur gear, to which motion is given by a spring, A'.

B is a pinion meshing into A.

20 C is a crank-arm fixed on the shaft B' of the pinion B.

F is an electro-magnet. F' is its armature, attached to the arm F², that is fixed to the rock-shaft F³. To this shaft is also fixed one end 25 of an arm, H, at the opposite end of which is the escapement devices, to be more particularly described presently. h and h' are pins fixed in a bracket, h², that limit the movement of the said arm H, and between which it may 30 vibrate.

h³ is a spring which acts to draw the lower end of H against the pin h whenever the armature is released from the magnet.

G is a lever pivoted at e, and H is an arm 35 fixed on the shaft F³. The lower end of this arm H may be forked, as shown in Fig. 1, and the two branches f and f' of the fork have respectively notches f² and f³ on their inner edges; the branch f being somewhat longer 40 than the branch f' and the notch f² somewhat below notch f³. Below the notches the branches may be beveled or rounded off on their inner edges, as shown in Fig. 1.

In the outer end of the arm i of the lever G 45 is a pin, n, projecting from its side, so placed that when said arm is thrown up, as in Fig. 1, said pin will pass into said fork of the lever H

above the notches f² and f³. g is a spring acting to depress said arm i of the lever G.

h and h' are pins projecting from a bracket, 50 h², between which the arm H may vibrate and by which its vibrations are limited.

h³ is a spring acting to draw the arm H against the pin h.

I is a cam fixed on the shaft B'. Projecting 55 from the side of the outer end of arm i' of the lever G is a pin, j, which engages the said cam. The outer end of the shaft e projects somewhat beyond the bracket, or part of the frame in which it has its bearings, and is cut away 60 on one side, so that the projecting portion e' is eccentric to the center of the shaft.

On the lower end of the crank-arm C is a pin or finger, k, Fig. 2, which projects inward, and is so arranged that when the arm i of lever G 65 is thrown up, as shown in Fig. 1, the projection e' is in the track of the finger k when the crank-arm C is revolved, but is carried above and out of said track when the said lever is released from the arm H and the arm i of said lever is 70 drawn down, as it will be, by the spring g.

Instead of the end of the shaft e on which the lever G swings being used to stop the crank-arm C, a pin or lug may be fixed at any point on the said lever where it will stand in 75 the track of the finger k when the lever is thrown up into engagement with the arm H, as in Fig. 1, and will be thrown out of the said track when the said lever becomes disengaged from the said arm and swings away from it. 80 When such pin or lug is employed as a stop, the track of the pin k should still be across the axis of the shaft e, so that the blow of the finger k on the said stop-pin should be taken directly by the said shaft, and thereby have no 85 tendency to swing the lever G on its pivot.

I have described what I consider the preferable form of the escapement at the lower end of the arm H; but I do not intend to limit myself to the special form described. Any 90 other equivalent form and arrangement of parts may be employed, whereby the end of the arm i of lever G is caught and detained in engagement with the arm H when swung up to

it, and is disconnected from said arm H when the latter is made to shift its position by the opening or closing of the circuit through the magnet. For example, pins may be used instead of the notches in the forked end of the arm H, said pins being made to project from the side of the lower one a little above the other, in the relative positions of the notches f^2 and f^3 , and the pin n arranged to engage 5 the said pin in arm H. I have also described my duplex escapement as employed to stop and let off a revolving arm or lever; but it is evident that it may be employed equally well in stopping and letting off mechanism in which 10 the part that engages onto the stop is constructed to move in a right line. I have represented in the drawings this duplex escapement as connected with the hammer for striking an alarm on a gong or bell as it may be 15 used in a fire-alarm telegraph. D' is the hammer-head, and D the hammer-lever, which is arranged to swing loosely on a pin, a. E is a link-bar, jointed to the crank-arm C at b and at c to the arm d on the lever D. By these 20 devices it is evident that a blow will be given by the hammer D' at each revolution of the crank-arm C; but it is evident that this duplex escapement can be used in other mechanism 25 where it is to be operated by the armature of an electro-magnet.

The operation of this apparatus is as follows: Suppose it is to be used in a fire-alarm telegraph that employs the closed circuit, or a circuit which is kept closed except when opened to 30 sound an alarm. In such circuit, the armature being held to the magnet, the lower end of the arm H will be swung against the pin h' and the pin n in the end of the arm i of lever G will rest on the notch f^2 . In this position the finger k is stopped against the projection e', and the apparatus is held at rest. Then, if the circuit is broken, the arm H will be drawn against the pin h by the spring h³, releasing the pin n from the notch f^2 , when the 35 arm i of lever G will be drawn down, thereby turning the projection e' up out of engagement with the finger k on the crank-arm C, thereby releasing that arm and leaving it free to make a revolution and cause a blow to be struck by 40 the hammer D' on the bell or gong D'', as before described; but when the arm C has completed its revolution the projection e' will be again in the track of the finger k and stop its movement, for the cam I, which revolves with 45 the crank-arm C, will act to carry outward the arm i of lever G, (which by the dropping of the arm i had been tilted in toward the center of the cam,) and thereby turn the projection e' into said track. At the same time the arm i 50 will be thrown up so that the pin n will engage again one of the notches f^2 or f^3 , thereby restoring the parts to their first or normal positions and bringing the apparatus to a state of rest. If the circuit should be closed when 55 the revolution of the arm C and cam I has been completed, the finger n, on its return upward,

will fall into the notch f in position to be disengaged therefrom when the circuit shall be again opened; but if upon the said return of the pin n the circuit is still open said pin will 70 engage with the notch f^3 , and then, upon the circuit being closed, will fall down onto notch f^2 , thus bringing the apparatus to its normal position.

If an open circuit is used, it is only necessary 75 to reverse the positions of the branches f and f' and the notches f^2 and f^3 , making the inner branch the shorter and the outer branch the longer one.

I am aware that a mechanism for striking 80 a gong or bell, consisting of a crank actuated by a spring through a spur-gear and pinion and a hammer operated by the said crank-arm by means of a link-bar similar to that I have shown and described, is in common use. With 85 such mechanism an escapement is employed consisting of a lever actuated by the armature of an electro-magnet, in which armature-lever is a pin that stops the crank-arm C, and which is disengaged from and removed from the track 90 of the finger k by the movement of the armature. I do not claim such devices, my claim being limited to the combination, with the arm H or its equivalent, actuated by the armature of an electro-magnet, and the crank-arm C or 95 its equivalent, of a second lever, which carries or moves the device that stops the said arm C and itself is locked in position to stop the said arm by engagement with the armature-lever, and is disengaged therefrom by the movement 100 of the armature of the magnet. In this combination of devices there is provided a stop that can take the force of the blow of crank-arm C without being liable to give way or shift its position, and thereby allow the said arm to 105 pass it and make a revolution when not intended to do so—a result which is apt to occur when the stop-pin is in the armature-lever. By the employment of the second lever described only a slight force is rendered necessary to let 110 off the escapement, thus making only a very small magnet and battery-power requisite. It is evident, therefore, that the duplex escapement described will work with great ease and certainty and without shock, although a large 115 power should be exerted by the mainspring or its equivalent in actuating a hammer or other mechanism with which the said escapement may be connected.

What I claim as my invention, and desire to 120 secure by Letters Patent, is—

1. The duplex electro-magnetic and mechanical escapement consisting of the magnet F, with its pivoted armature and swinging arm H, provided with escapement devices consisting of the forked ends f and f' of said lever, provided with notches f^2 and f^3 on inner edges thereof, and the lever G, having pin n, and constructed and arranged to engage the arm H and to actuate a stop device, as and for the 125 purpose described.

2. The combination of the magnet and arma-

ture, the arm H, lever G, stop e' , crank-arm C, cam I, and spring g , as and for the purpose described.

3. The combination, with the hammer D and gong D^2 , the revolving crank-arm C and link-bar E, of the escapement mechanism described, consisting of the magnet F, with its pivoted

armature F', arm H, lever G, stop e' , cam I, and springs g and h^3 , all constructed to operate as and for the purpose described.
